UNITED STATES PATENT OFFICE.

HOWARD K. KING, OF PHILADELPHIA, PENNSYLVANIA, ASSIGNEE TO CHAMBERS BROTHERS COMPANY, A CORPORATION OF PENNSYLVANIA.

FOLDING-MACHINE.

1,071,755.

Specification of Letters Patent.

Patented Sept. 2, 1913.

Application filed October 27, 1911. Serial No. 657,034.

To all whom it may concern:

Be it known that I, HOWARD K. KING, a citizen of the United States, residing at Philadelphia, in the county of Philadelphia, State of Pennsylvania, have invented a new and useful Folding-Machine, of which the following is a specification.

My invention relates to improvements in sheet folding and insetting machines.

My object is to provide improved means whereby a sheet is given a required number of folds, then cut into sections, and sections folded and one delivered independently or else superimposed and insetted one section 15 within another.

The invention comprises means whereby the sheet sections are delivered into different planes and then moved forward in the same direction, certain sheets into the folding position, and then other of said sheet sections are moved transversely into the folding position.

The invention comprises means whereby each sheet section is struck separately 25 through the last pair of folding rollers, or else two superimposed sheet sections are struck together through the final folding rollers so that one may be insetted in the other.

Referring to the drawings illustrating by way of example suitable means for effecting my invention—Figure 1 is a plan view. Fig. 2 is a vertical section on line 2—2 of Fig. 1. Fig. 3 is a vertical section on line 3—3 of Fig. 1. Fig. 4 is a fragmentary plan view of a cutting roller and associated mechanism. Fig. 5 is a vertical section on line 5—5 of Fig. 4. Fig. 6 is a vertical section on line 6—6 of Fig. 4. Fig. 7 is a sectional detail on an enlarged scale of the striking blade and folding rollers. Fig. 8 is a front elevation of the cam for actuating the insetting striking blade. Fig. 9 is a side elevation of same. Fig. 10 is a fragmentary detail in section on line 10—10 of Fig. 6, but on a reduced scale.

Similar numerals refer to similar parts throughout the several views.

As a large part of the mechanism utilized for effecting the present invention, is not new, it will only be necessary to refer to such parts in indicating the preliminary travel and folding of the sheets. For ex-

ample, referring to Fig. 2, the sheet is received between the feed roller 20 and the drop roller 21, in the usual way, and carried to position beneath the striking blade 22, by which it is struck between the rollers 23, for the first fold. The folded sheet is then carried to position beneath the striking blade 25, by which it is struck between the rollers 24, for the second fold. It is then delivered to the cutters 26 and cutting rollers 27, 28 and 29.

As will be noted the present machine is provided with three cutters thus serving to cut the folded sheet into four parts.

The arrangement of the tapes is such that the two middle parts or sheet sections, 36 and 37, are carried between rollers 32 and 33 onto the tapes 30 and 31, while the two outer sheet sections 38 and 39 are carried around the cutting rollers 27 and 29 onto tapes 34 and 35, see especially Figs. 4 and 6. It will thus be seen that the outer sheet sections are carried forward horizontally on a plane higher than the two inner sheet sections. Sheet section 38 is carried forward to a point in the folding position over folding rollers 40 and 41, as shown in Fig. 1, while sheet section 39 is brought to a position over folding rollers 42 and 43. Sheet section 36 is carried forward simultaneously as before stated, on a lower plane but substantially the same distance as sheet section 38, while sheet section 37 is similarly carried forward the same distance as sheet section 39, but upon a lower plane.

When it is desired to operate the machine to deliver four signatures of sixteen pages each, the machine is operated so that the striking blades 50 and 53, Figs. 3 and 7, strike sheet sections 39 and 38 through the slits 51 and 54, and the folding rollers 42 and 43 and 40 and 41 respectively, while sheet sections 36 and 37 rest in the position shown in Fig. 3, that is to say, the striking blades 50 and 53 are actuated by the cams 63 and 62 respectively. These cams are each provided with the two drops or depressions 64 and 65, see Figs. 8 and 9. These cams are geared relatively to the cams 48 and 49, which actuate the drop rollers 45 and 47 respectively which coöperate with the feed rollers 44 and 46. These drop and feed rollers cause the movement of sheet sections

36 and 37 into the folding position beneath said striking blades 53 and 50 respectively whereby, upon the next descent of the striking blades due to the second recess in the 5 cams 62 and 63, the sheet sections 36 and 37 are struck through the rollers 40 and 41 and 42 and 43 to receive the final fold. The sheets struck through rollers 42 and 43 are delivered through the guide slit 56 to the 10 packing trough 57, while the sheets struck through rollers 40 and 41 are carried by the tapes 58 and 59 downwardly through the guide slit 60 into trough 61. It is obvious that in such case the packer in these troughs, 15 not shown, is located in the middle, packing the sheet sections 37 toward one end and the sheet sections 39 toward the other end of the trough. In like manner the packer in trough 61 is similarly arranged to pack the 20 sheet sections 36 toward one end and the sheet sections 38 toward the other end. When however, it is desired that the machine should operate not to deliver four signatures of sixteen pages each, but two signatures of thirty-two pages each, it is simply 25 necessary to prevent the alternate strokes of striking blades 50 and 53, so that the sheets 36 and 37 may be carried by their respective drop and feed rollers beneath sheets 38 30 and 39 respectively, but in register therewith. This is accomplished by placing a shield 66 in one of the depressions of each of the cams 62 and 63, so that there is one actuation only of the striking blades 50 and 53, 35 with each revolution of its respective actuating cam. That is to say, after the sheets 36, 37, 38 and 39, all reach the position shown in Fig. 1, there is a pause in the operation of the said striking blades 50 and 53, 40 until 37 is brought beneath 39, and 36 brought beneath 38, whereupon the striking blade 50 strikes 39 through slit of plate 51 and then carries it with sheet 37 through slit members 52 and folding rollers 42 and 45 45 13, thereby folding 37 with 39 insetted. In a corresponding way 36 is folded with 38 insetted, in which case the packers in the packing troughs 57 and 61 are arranged to pack the signatures in each trough all together in one direction. 50

The operation above described delivers what is called a double 32, that is, two signatures of 32 pages each.

It will thus be seen that by controlling 55 the period of the stroke of the folding blades 50 and 53, is determined whether the said sheet sections are struck individually between the respective folding rollers, or whether the folding blades pause until 37 60 and 39 are superimposed and 36 and 38 are superimposed.

Means for transverse movement of sheet sections 36 and 37.—It will be understood that after passing the cutters, the several 65 sheet sections move in direction at right an-

gles to the axis of the cutters and cutting rollers, until they reach the positions shown in Fig. 1. It is then necessary to cause a transverse movement, in opposite directions, of sheet sections 36 and 37, in order to 70 bring said sheet sections beneath the striking blades 53 and 50 respectively.

Referring to Fig. 3, the sheet sections 36 and 37 are shown in the position at the end of their movement after passing the cutters. 75 The feed rollers 44 and 46 are adapted to act upon the said sheet sections 36 and 37 respectively, causing the movement of the same to the right and left respectively, upon the co-operation with said feed rollers of the drop rollers 45 and 47. These drop rollers are actuated by the cams 48 and 49, 48 only showing in Fig. 3, as 49 is directly behind it as shown in Fig. 6. These cams are of course so proportioned and operated relatively to the other mechanisms as to secure the desired periodicity of actuation of the drop rollers. 85

It will be noted that sheet section 37 is moved by the drop and feed rollers 47 and 90 46 to the left, along the steel guide 81, until said sheet section enters between folding roller 43 and the friction roller 82, whereby it is carried farther on to the left over the slit member 52 between the idler 83 and 95 friction roller 84, along the guide rods 85, until it is brought to rest by the stop 86.

It will be noted that one of the slit members 52 has a shield extending to the left over the roller 42. This is provided to prevent the edge of the sheet section coming into contact with roller 42, which, traveling in direction opposite to the travel of the sheet section, would tend either to retard the movement of the sheet section, or prematurely to drive it between the folding rollers. In order to make room for this shield extension of the slit member, the top surface of which is substantially in the plane of the top of roller 43, roller 42 is made of less diameter than roller 43. To prevent distortion of the sheets passing between folding rollers 42 and 43, roller 42 is driven, by suitable gearing not shown at a slightly greater angular speed than roller 43, so that 110 the said rollers shall have the same peripheral speed of rotation. Roller 83 is driven in a direction opposite to that of roller 42 either by direct friction engagement therewith, or by suitable gearing. 115

The mechanism for causing the transverse movement of sheet section 36 is the same as that above described with respect to sheet section 37.

Adjustable spring controlled yielding support for cutter rollers and guide rollers.—To secure a more uniform pressure between the guide rollers, and the cutter rollers, I provide the following mechanism for the guide rollers: The several brackets 71 are 120 125

slidably mounted on the members 69 and 70. To one of these brackets 71 is pivoted the hanger 72 at the point 74 as shown in Fig. 6. In Fig. 5 the hanger indicated by the number 73, is substantially the same as hanger 72, except it is provided with guides which will be described later on. The hanger 72 carries the middle cutter. The flanking cutters are carried by hangers 73. These hangers 72 and 73 are partially bifurcated and carry the cutting wheels and guide rollers 26. A spring 75 is connected between the hanger and the boss 76 on bracket 71. The hanger is also provided with a lug 77 which co-operates with the lug 78 on the bracket 71, for limiting the spring actuated movement of the hanger. It will be noted that there is a sufficient play between the lugs and the abutting parts to allow a slight rocking movement of the hanger. This gives the necessary yield between the guide rollers and the cutting rollers to assure a uniform feed of the sheets in the cutting operation. It follows of course that where intermediate or supplementary rollers are used for additional guides to the paper in connection with the cutters or cutter rollers these may be similarly supported to secure an even feed of all parts of the sheet. It is also obvious that the tension of the spring 75 may be adjusted by a suitable screw in lug 76 or by other suitable means.

Lateral adjustment of the cutters and guide rollers.—In order to conveniently adjust the cutters for different sized sheets the following means have been provided. The machine is provided with a stationary rail 68 running across the machine. On this rail are mounted the sliding members 69 and 70. Upon these members are mounted all of the brackets 71, except the middle one, which is secured on a stationary bracket connected with rail 68. The sliding members 69 and 70 are then actuated by suitable hand wheels and screws as shown in Fig. 4. It will also be understood that the outer brackets 71 are independently adjustable on the sliding members 69 and 70, so that they may be correspondingly adjusted by slot and bolt engagement for larger or smaller sheets.

Adjustment of cutting rollers.—In order to adjust the cutting rollers so that their grooves will correspond and co-operate with the cutters, I provide the following mechanism: The shaft 87 carries all of the cutting rollers 27, 28 and 29. The roller 28 is fixed on said shaft while rollers 27 and 29 are feathered on said shaft and are longitudinally movable thereon. The brackets 88 and 89 are also secured to the sliding members 69 and 70, which carry the two outer brackets 71. These brackets 88 and 89 project into annular channels 90 and 91 in rollers 27 and 29 respectively, so that as the members 69 and 70 are moved along

the bar 68 the rollers are always kept in proper register with their respective cutting wheels.

Guides for directing sheet sections into different planes.—It will be noted that sheets 36 and 37 are delivered from the cutting rollers to a different plane from that to which sheets 38 and 39 are delivered. That is to say, as the original sheet is being cut into the four sheet sections, by the cutting wheels, two sections that is 38 and 39, are guided around cutting rollers 27 and 29, onto the tapes 34 and 35, while the sheets 36 and 37 are guided down between rollers 32 and 33, to a lower plane and delivered onto the tapes 30 and 31. To assure the proper respective travel of the several sheets, I provide, in connection with two of the cutter wheel supports 78, the curved guide 79, on one side of the cutting wheel 25 to direct the sheet around the roller 27 or 29, onto tapes 34 and 35 as the case may be, while upon the other side of the cutting wheel I provide the guide rod 80 which deflects the adjacent sheet section downwardly so that it will pass between rollers 32 and 33, that is, these two guides 79 and 80, assure the proper direction of travel of the adjacent sheet sections as the same are being cut and effectually prevent a tendency of the same sticking together or following the same line of travel.

What I claim is:—

1. In a sheet folding machine, the combination of means for folding each sheet and then cutting it into a plurality of sections, means for delivering pairs of said sections so that one section of a pair shall superimpose another, one section of each of said pairs of sections being delivered directly from the cutting means into a different plane than that of the other section of the pair, and means for striking the sections of each pair together one inserting the other in a final fold.

2. In a sheet folding machine, the combination of means for folding each sheet and then cutting it into a plurality of pairs of sections, means for delivering adjacent sections of each pair, as they are being severed, into different planes, and means for then moving one section of each pair, in a direction transverse that of its first movement, until one section of each pair superimposes the other.

3. In a sheet folding machine, the combination of means for folding each sheet and then cutting it into four sections, means for folding said sections into four signatures of sixteen pages each, or into two signatures of thirty-two pages each, said means comprising two pairs of slotted members, one member of each pair superimposing the other, means for bringing pairs of the sections into registering position, but one in

- time subsequent to the other, striking blades and arbitrary means for timing said striking blades to strike each section separately or a pair of sections together.
5. In a folding machine, the combination of means whereby a sheet is folded and separated into a plurality of sections, said sections delivered from the separating means onto carrying tapes traveling in the same direction but in different planes, drop and feed rollers adapted to operate upon the sheets in one plane to cause their transverse movement to register with the sheets lying in another plane, and final folding rollers and a striking blade for folding said registered sheet sections one insetted within another. 70
6. In a sheet folding machine, the combination of means for folding each sheet and then cutting it into four sections, means for carrying the sections forward in pairs, one of each pair in a different plane from the other of said pair, means for moving one of each pair transversely of its first movement, so that the sections of each pair shall register with each other, one reaching its position in time subsequent to the other, striking blades and means for controlling the movements thereof, either to strike each pair together in the final fold, or to strike each section of each pair independently of the other. 80
7. In a sheet folding machine, the combination of means for folding and cutting each sheet into a plurality of pairs of sections, means for moving all the sections forwardly, one of each pair directly to its folding position, means for then moving the other of each pair in direction transverse to the direction of its first movement, a distance equal to one of its dimensions, into position that one of each pair will superimpose the other, slotted members, means for striking said sections through the same, and arbitrary means for timing the striking means to secure the separate folding of each section, or the folding of each pair of sections together, one insetting the other. 90
8. In a folding machine, the combination of means for folding a sheet and then cutting the same into a plurality of sections, said cutting means comprising cutting wheels, guide rollers and coöperating cutting rollers, a cutting wheel and guide roller supporting hanger, a bracket pivotally connected with the hanger, a spring operating between the bracket and hanger and means for permitting limited play of the hanger with respect to the bracket. 100
9. In a folding machine, the combination of means for folding a sheet and then cutting the same into a plurality of sections, said cutting means comprising cutting wheels, guide rollers and coöperating cutting rollers, a cutting wheel and guide roller supporting hanger, a bracket pivotally connected with the hanger, a spring operating between the bracket and hanger and a lug on the hanger and a coöperating lug on the bracket for limiting the spring controlled play of the hanger. 105
10. In a folding machine, the combination of means for folding a sheet and then cutting the same into a plurality of sections, said cutting means comprising cutting wheels, guide rollers and coöperating cutting rollers, a cutting wheel and guide roller supporting hanger, a bracket pivotally connected with the hanger, and an adjustable supporting body for the hanger. 110
11. In a folding machine, the combination of means for folding a sheet and then cutting the same into a plurality of sections, said cutting means comprising cutting wheels, guide rollers and coöperating cutting rollers, a cutting wheel and guide roller supporting hanger, a bracket pivotally connected with the hanger, a spring operating between the bracket and hanger and an adjustable supporting body for the bracket. 115
12. In a folding machine, the combination of means whereby a sheet is folded and cut into a plurality of sections and means whereby adjacent sections are delivered into different planes, comprising a cutter wheel, a curved guide for directing one sheet section toward the horizontal direction on one side of the cutter wheel and a downwardly projecting guide for engaging another sheet section on the other side of the cutter wheel. 120
13. In a folding machine, the combination of means whereby a sheet is folded and cut into a plurality of sections and means whereby adjacent sections are delivered into different planes, comprising a cutter wheel, a curved guide for directing one sheet section toward the horizontal direction on one side of the cutter wheel, a downwardly projecting guide for engaging another sheet section on the other side of the cutter wheel, and tapes traveling in different horizontal planes for coöperating with said guides. 125
14. In a folding machine, the combination of means whereby a sheet is folded and severed into a plurality of sections, means for delivering severed sections into different planes, and means for causing a transverse movement of a sheet section, 130

comprising a suitably operated drop and feed roller, guides and a folding roller and a friction roller.

15. In a folding machine, the combination of means whereby a sheet is folded and severed into a plurality of sections, means for delivering severed sections into different planes, and means for causing a transverse movement of a sheet section comprising a suitably operated drop and feed roller, a pair of folding rollers, a friction roller cooperating with one folding roller, a shield for the other folding roller, an idler driven by the latter folding roller and a coöperating friction roller.

16. In a sheet folding machine, the combination of means for folding each sheet and then cutting it into four sections, means for carrying all the sections forwardly, the outer sections in a plane different from that of the inner sections, means for then carrying the inner sections transversely to their first movement until, of each pair one superimposes the other.

17. In a sheet folding machine, the combination of means for folding each sheet and then cutting it into four sections, means for carrying all the sections forwardly, the outer sections to folding position, and in a plane different from that of the inner sections, means for then carrying the inner sections transversely to their first move-

ment until, of each pair one superimposes the other.

18. In a sheet folding machine, the combination of means for folding each sheet and then cutting it into four sections, means for carrying all the sections forwardly, the outer sections in a plane different from that of the inner sections, means for then carrying the inner sections transversely to their first movement until, of each pair one superimposes the other, and means for striking the sections when in folding position.

19. In a sheet folding machine, the combination of means for folding each sheet and then cutting it into four sections, means for carrying all the sections forwardly, the outer sections in a plane different from that of the inner sections, means for carrying the inner sections transversely to their first movement, said transverse movement effecting, if insetting is desired, the superimposing of one section of each pair by the other section of said pair, means for striking the sections when in folding position, and means for arbitrarily controlling the striking actuation, either to strike the sections separately, or else to strike the pair of sections together, one insetting the other.

HOWARD K. KING.
